(57) **CLAIM**

The ornamental design for a handbag, as shown and described.

DESCRIPTION

The file of this patent contains at least one drawing/photograph executed in color. Copies of this patent with color drawing(s)/photograph(s) will be provided by the Office upon request and payment of the necessary fee.

Fig. 1.1: is a Perspective view of a handbag showing my new design;

Fig. 1.2 is a front view thereof; and

Fig. 1.3 is a back view thereof; and

Fig. 1.4 is a right view thereof; and

Fig. 1.5 is a left view thereof; and

Fig. 1.6 is a top view thereof; and

Fig. 1.7 is a bottom view thereof.

The portion of the design shown in the color “Yellow” is for the purpose of illustrating a portion of the article that forms no part of the claimed design. The broken lines on portions of the handbag represent stitchings which form no part of the claimed design.

1 Claim, 7 Drawing Sheets
